(57) **CLAIM**

The ornamental design for a watch as shown and described.

DESCRIPTION

FIG. 1 is a front plan view of a watch illustrating our new design;

FIG. 2 is a back plan view of the design of FIG. 1;

FIG. 3 is a right side elevational view of the design of FIG. 1;

FIG. 4 is a left side elevational view of the design of FIG. 1;

FIG. 5 is a top plan view of the design of FIG. 1;

FIG. 6 is a bottom plan view of the design of FIG. 1, which is a mirror image of FIG. 5; and,

FIG. 7 is a front, bottom right perspective view of the design of FIG. 1.

The broken lines shown in the drawings represent portions of the watch that form no part of the claimed design.

1 Claim, 7 Drawing Sheets
